UNITED STATES PATENT OFFICE.

FRANK CHASE, OF BOSTON, MASSACHUSETTS.

LASTING-TACK STRIP.

SPECIFICATION forming part of Letters Patent No. 337,662, dated March 9, 1886.

Application filed November 19, 1885. Serial No. 183,266. (No model.)

To all whom it may concern:

Be it known that I, FRANK CHASE, of Boston, in the county of Suffolk and State of Massachusetts, have invented a certain new and 5 Improved Lasting-Tack Strip, of which the following is a specification.

The lasting-tack strip in which my invention is comprised consists of wire of suitable cross-section, which at intervals is bent into loops, 10 the legs of which are pressed together and otherwise manipulated so as to form stems with pointed ends, said stems being either corrugated or not, as desired. In this way I produce economically and with facility a strip 15 having tacks connected together and put into shape in which they can be conveniently and effectively used.

In the accompanying drawings, Figure 1 is a view of the wire from which the lasting tack 20 strip is to be made. Fig. 2 represents the strip after the wire has been bent into loops at intervals. Fig. 3 represents the completed strip—that is to say, the strip after the loops have had their legs squeezed together and their 25 ends pointed.

A, Fig. 1, is the wire, of any suitable metal and of any suitable shape in cross-section. This wire by suitable means is bent at intervals into loops, *a*, as indicated in Fig. 2, and 30 each loop is then squeezed so as to bring its legs closely together in the form desired for the shank or stem of the tack, and its end is pointed, all as indicated in Fig. 3.

The squeezing and sharpening operations

can be readily effected by means of suitable 35 dies, which dies may be the same in which the loops are formed, or separate instrumentalities for squeezing and sharpening may be employed.

In this way I produce with ease and at small 40 cost a lasting-tack strip consisting of wire formed into a series of connected tacks. The intervals between the tacks can vary as desired. The strip can readily be used, and the tacks can be readily severed as required. The 45 wire can, if desired, be corrugated, or the tacks themselves can be corrugated in the dies by which they are formed. Furthermore, if desired, the wire can be so formed throughout its length as to be thicker at the points where 50 the bends or bights of the loops will come, thus putting more metal into the loops—the point where it is needed in order to insure the formation of a proper point on the tack.

Having described my invention, what I 55 claim, and desire to secure by Letters Patent, is—

A lasting-tack strip consisting of wire bent at intervals into loops, pressed into tack form, and pointed, substantially as and for the purposes hereinbefore set forth.

In testimony whereof I have hereunto set my hand this 5th day of November, 1885.

FRANK CHASE.
